POPCORN CONTAINER

Andrew J. Krappman, Los Angeles, Calif., assignor to Fox West Coast Theatres Corporation, Los Angeles, Calif., a corporation of Delaware

Application August 6, 1948, Serial No. 147,983

Term of patent 14 years

(Cl. D58—4)

To all whom it may concern:

Be it known that I, Andrew J. Krappman, a citizen of the United States, residing in Los Angeles, in the county of Los Angeles and State of California, have invented a new, original, and ornamental Design for a Popcorn Container, of which the following is a specification, reference being had to the accompanying drawings, forming a part thereof.

The drawing is shaded to indicate contrasting appearance.

I claim:

The ornamental design for a popcorn container, as shown and described.

ANDREW J. KRAPPMAN.
